Samuel E Babcock
Searched Patent

The Schedule referred to in these Letters Patent and making part of the same containing a description in the words of the said Samuel E. Babcock himself of his improvement in the machine for mortising timber.

To all to whom these presents shall come. Be it known that I, Samuel E. Babcock of Alstead in the County of Grafton and State of New Hampshire have invented a new and useful improvement in the art of mortising, a machine for mortising holes or openings in timber and that the following is a full and exact description thereof reference being had to the annexed drawings. Fig. 1 a perspective view of the machine. The frame of which is made of timber three inches square and put together in the usual way with mortises and tenons, being three feet long, one foot six inches wide and two feet four inches high and is composed of eleven ^{one} ~~one~~ four posts A, four eight inches B, two at the top and two near the bottom of the posts A. and two long rails C. connecting the posts at the top, also one long rail through the middle of the top connecting the two upper short rails. Midway between the top and bottom short rails of the frame a long rail D. is attached to the back posts by means of bolts see D. The top of this frame is covered with thick hard wood board which is made fast with screws. Through this board a hole is cut against the back of the middle rail one foot four inches long and three inches wide. Through this opening two ponderous posts are placed being made of timber three inches square and are ~~square~~ fast at the lower end to the rail D. with bolts. These ponderous posts are connected at the top by a timber of the same size and ten inches long. Between these posts which are made fast to the middle rail

330.

part of the machine. The gate B. two feet long and ten inches wide and made of timber two inches thick plays up and down in grooves in the fence posts. To the lower end of this gate a scoop is attached which reaches down to the lever C. having a mortise in the lever and is made fast with a pin. This lever is made fast to the roller D. which turns between the two standards of the machine. The lever being three feet long and sweeps the roller at right angles at the back end of the lever a weight is attached to throw up the gate. C. is a head block of iron set on the upper cross piece of the gate and is made fast at any situation required by a set screw. D. is a round hole in this head block C. is made fast by means of the set screw E. Operation. place the timber on the table of the machine against the fence post and the foot on the lever pressing it down and the chip into the timber. Now by raising the foot the weight on the opposite end of the lever will throw up the gate, throwing the chip out of the timber by separating the ^{some} ~~the~~ ^{some} operation the snow ^{the} may be cut to the required length.
